UNITED STATES PATENT OFFICE.

ALEXANDER RODGERS, OF MUSKEGON, MICHIGAN.

FEED-WATER HEATER.

SPECIFICATION forming part of Letters Patent No. 316,182, dated April 21, 1885.

Application filed September 10, 1884. (No model.)

To all whom it may concern:

Be it known that I, ALEXANDER RODGERS, a citizen of the United States, residing at Muskegon, in the county of Muskegon and State of Michigan, have invented certain new and useful Improvements in Feed-Water Heaters for Steam-Boilers, of which the following is a specification, reference being had therein to the accompanying drawings.

10 This invention relates to improvements in that class of feed-water heaters used in connection with the ordinary two-flued or tubular boilers commonly employed for generating steam for stationary engines in mills and mining-works; also for supplying steam on the steamers of the western rivers. These boilers are set in brick arches, frequently several boilers side by side in the same arch. The grates are placed beneath one end, and the 15 products of combustion, after passing a bridge-wall which comes up nearly to the bottom of the boilers, pass under them to their rear ends, where they are met by the rear wall of the arch, placed a short distance back of the 20 rear end of the boilers. By this wall they are turned upward and enter the flues or tubes of the boilers, by which they are brought forward to the front of the boilers again, and pass thence to the smoke-stack. A difficulty has 25 been experienced in boilers set in this way in keeping the space between the rear wall of the arch and the rear end of the boilers properly covered, as the expansion and contraction of the boilers soon break up a fire-brick arch, or 30 the large bricks reaching from the wall to the boiler sometimes employed. Another device employed for covering this space consists of cast-iron plates secured at one side to the boilers, and the other resting loosely upon the top 35 of the wall, so as to slide back and forth as the boilers are lengthened or shortened under the influence of heat; but these plates are defective from the fact that the intense heat to which they are exposed soon cracks and de- 40 stroys them. To find a remedy for this trouble is one of the objects of my invention. Another is to save the heat which has hitherto been worse than wasted in destroying these plates or other coverings of the space between 45 the boilers and arch by causing it to assist in heating the feed-water which enters the boil-

ers; and a further object is to increase the efficiency of the feed-water heater by a novel construction which enables it to thoroughly filter the water passing through it, and relieve it from the injurious jar of the feed-pump or other feeding apparatus.

55 My invention therefore consists in the novel construction and arrangement of parts with relation to the boilers of a feed-water heater, 60 as will be hereinafter fully set forth, and then specifically pointed out in the claims.

In the accompanying drawings, Figure 1 represents a rear elevation of the boilers and arch, the back wall being removed and the 65 feed-water heaters shown in longitudinal section. Fig. 2 is a plan of the rear portion of a set of boilers, the arch and feed-water heater, showing their relative arrangement. Fig. 3 is a side elevation, the side wall of the arch 70 being removed, showing a side of one of the boilers, one end of the feed-water heater and mud-drum, with their connections. Fig. 4 shows one of the perforated diaphragms of the feed-water heater upon an enlarged scale.

75 The boilers in these drawings are indicated by A A, and may be of the common two-flue variety, (shown as having return-tubes instead of the flues,) the improved feed-water heaters being adapted for use with any boiler having 80 its grates placed below and returning the products of combustion through flues or tubes.

B B are the side walls of the boiler-arch, and B' the rear wall.

C is a mud-drum placed transversely across 85 the arch beneath the boilers and connected with each of them by a short pipe or connection, a.

D is the drum forming the outer portion of the heater, placed transversely across the arch 90 in the rear of the boilers, its ends resting on the side walls and partially supported by the rear wall, as shown in Fig. 3, its bottom and front sides covering the space between the wall and rear end of the boilers above the flues, except a narrow space left between the boiler ends and the heater to allow the necessary movement of the boilers as they expand or contract. This space may be covered by a brick, as shown at b. Through this heater 95 from end to end passes the exhaust-pipe E of an engine, as F. This exhaust-pipe prefera-

bly passes through the heater above its axial line, and is provided at its outlet with suitable connections for carrying the exhaust-steam to the smoke-stack or delivering it into the open air, as may be desired. At suitable distances from each other within the heater are placed the perforated diaphragms *c c*, inclosing a space or chamber, *G*, between them, to which access is obtained through the hand-hole *d* in the top of the heater. This chamber *G* is filled with hay or other suitable material, which not only filters the water, but, in the case of water impregnated with lime or other mineral matters, in conjunction with the heat, causes it to throw down the whole or a large proportion of these substances that may be held in solution.

The feed-water enters the heater through the pipe *e*, becoming heated to a considerable degree while in the chamber *H*, which occupies the larger part of the heater, and is provided with the air-chamber *I*, which relieves the heater from the shocks of the feed-pump, causing the pressure within it to remain uniform. From this chamber *H* the feed-water passes through the filter *G* into the chamber *H'*, and from this by means of the pipe *g* it is conveyed to the mud-drum *C*, whence it passes by the connections *a* into the several boilers forming the set.

I am aware that feed-water heaters have been constructed in which the direct heat from the products of combustion as well as the heat from the exhaust-steam has been employed to

heat the feed-water, and do not therefore broadly claim such a combination; but

What I do claim as new, and desire to secure by Letters Patent, is as follows:

1. A feed-water heater consisting of a horizontally-placed cylindrical drum extending across the boiler-arch in the rear of the boilers, and covering the space between the ends of said boilers and the back wall of the arch, said drum containing a passage for the exhaust-steam, chambers *H* and *H'*, and filtering-chamber *G* and air-chamber *I*, all arranged for joint operation in the manner described. 45

2. In a feed-water heater, the combination of the drum *D*, containing chambers *H* *H'*, and filtering-chamber *G*, with the air-chamber *I* and exhaust-pipe *E*, all arranged for joint operation in the manner described. 50

3. The combination, with an engine, a boiler or boilers, and a boiler-arch, of a feed-water-heating drum, *D*, placed horizontally across and closing the space between the rear ends of the boilers and the back wall of the boiler-arch, and an exhaust-pipe, *E*, that leads from the engine and passes through said drum, whereby the feed-water is heated by exhaust-steam and by direct action of the fire, substantially as described. 55 60

In testimony whereof I have affixed my signature in presence of two witnesses.

ALEXANDER RODGERS.
